UNITED STATES PATENT OFFICE.

JAMES HENRY STUTHRIDGE AND THOMAS MOXHAY HACK, OF JOHANNESBURG,
TRANSVAAL, SOUTH AFRICA.

MEANS FOR SUPPLYING WATER TO ROCK DRILLS AND THE LIKE.

Application filed March 24, 1927, Serial No. 177,966, and in the Union of South Africa May 25, 1926.

The invention relates to means for supplying water to rock-drills or rock-drilling machines, et cetera, of the kind in which the water is conveyed through the drill steel, bit or jumper to, or to a point in proximity to, the cutting end thereof, while the machines are in operation.

One object of the present invention is to construct simple and efficient means which, while allowing of the free passage of the water to the longitudinal or axial hole through the drill steel, bit or jumper, will preclude the escape of water in either a forward or, and more particularly, a backward direction, and so prevent the water from entering the front head, cylinder, or other operative parts of the drill or machine.

A further object is to devise means which will, if desired, obviate the necessity for machining or turning the drill shank or portion thereof around which the parts of the device are arranged, or so that a rough or plain rolled or forged drill steel can be used or have the invention applied to it with satisfactory results.

Means according to the invention may be termed a floating, automatic, water-tight packing device, which surrounds the drill steel, bit or jumper and revolves therewith.

The invention will be more fully explained in connection with the accompanying sheet of drawings, illustrating two practical embodiments of the same. In the drawings,

Fig. 1 is a plan view of a front portion of a rock-drill, with the invention applied thereto.

Fig. 2 is a front elevation of Fig. 1.

Fig. 3 is a central sectional elevation of the device, showing the drill steel, bit or jumper in position therein.

Fig. 4 is a view similar to Fig. 3, illustrating a slightly modified form of the invention, and

Fig. 5 is a sectional view of portion of the device, illustrating an alternative detail of construction.

Referring more particularly to that embodiment of the invention represented in Figs. 1, 2, and 3, the water supplying means or device includes what we may designate a water head 1, which may, as shown, be made as a separate or detachable part from the front head 2 of the machine, and be attached to the front end thereof by means of the ordinary longitudinal side bolts 3, for

which purpose the water head 1 may be constructed with lugs 4 to receive the ends of the bolts 3; 5 being the retaining nuts screwed on to the bolts 3 at opposite sides of the lugs 4. The water head 1 could, if desired, be constructed integral with the front head 2. The front end of the water head 1 is shown provided with a screw-thread to receive a screw-threaded cap or member 6, which is constructed in its front portion to serve as a guide 7 for the front portion of the shank 8 of the drill steel 9. Both the cap or member 6 and the water head 1 are constructed interiorly with raised surfaces 10 for a purpose hereinafter referred to. 70

The rear portion 11 of the shank of the drill steel may, as usual, be of square cross-section to engage with the ordinary rotation sleeve 12. 13 is the longitudinal water passage or hole through the drill steel or bit 9, and 14 a transverse hole formed in the portion 8 of the shank, and communicating with the longitudinal hole 13. As shown in Fig. 5 the cap or member 6 forming the front guide for the portion 8 of the shank of the drill may be fitted with a renewable wearing bush or liner 15, shown fashioned with a flanged inner end 16, on which flange a raised surface, similar to the surface 10 on the cap or member 6, is provided. 80 85

The head 1 is constructed with a water inlet branch 17 for making connection with the water supply pipe—not shown. The interior of the water head 1 provides a water space or chamber 18 around the parts of the device which surround the portion 8 of the shank of the drill steel or bit 9 and rotate with it within the water head 1. The inlet through the branch 17 communicates with the water space 18 in the head 1. The rear end of the portion 8 of the shank of the drill is made so as to be a loose fit in the head 1, and a plurality of radial ports or passages 19 are shown formed in the rear end of the head 1 to allow of the ready escape of any air that may leak in a forward direction, so precluding it from entering the water head 1. The head 1 at the rear end is shown constructed with a projection 20 adapted to project into the front end of the front head 2 of the machine to centre the device. 95 100 105

Within the water head 1 is arranged the automatic, water-tight packing means which includes two oppositely disposed rings 21, 22, of india-rubber comprising inner and 110

outer parts connected together at the outer ends, or in the form of U or ordinary hydraulic packing rings. These rings 21, 22, surround the enlarged portion 8 of the shank 5 of the drill steel, bit or jumper 9 and are positioned with their open inner ends facing or opposite each other. The rings 21, 22, are enclosed or housed in a cylindrical casing 23 which they more or less fit, and which 10 may be made of brass or other suitable non-corrosive material, and is exteriorly somewhat smaller than the interior of the water head 1, so forming the annular water space 18. The cylindrical casing 23, in this form 15 of the invention, is constructed interiorly with a central annular projection 24 which forms a distance piece between the inner ends of the packing rings 21, 22. The casing 23 is formed with a central peripheral groove 20 25 and with a central internal annular recess 26 in the projection 24. A ring or plurality of holes 27 are provided leading from the bottom of the groove 25 to the internal annular recess 26. The transverse hole 14 in 25 the portion 8 of the shank of the drill steel is in communication with the recess 26 in the normal operation of the machine, so that the water is free to pass from the water space 18 through the groove 25, radial holes 30 27 and recess 26 to said hole 14, and thence along the longitudinal hole 13 to the cutting end of the drill 9.

A plurality of lateral holes or passages 35 28 are formed in the projection 24, leading from the groove 25 to the sides of the projection 24 in front of the open ends of the packing ring 21, 22. Through these holes or passages 28 water is free to pass to the interior of the packing rings 21, 22.

40 In the ends of the casing 23 and abutting the outer ends of each of the india-rubber packings 21, 22, antifriction washers 29, 30, are placed, which may be of vulcanite, ebonite, phosphor bronze, or any other suitable metal or material. The washers 29, 30, are preferably a loose fit in the ends of the casing 23 and around the portion 8 of the shank of the drill steel or bit 9. The washers 29, 30, contact with the raised surfaces 10 45 at the opposite ends of the water space 18 in the water head 1 and make water-tight joints therewith.

It follows from the foregoing description 50 that the cylindrical casing 23, together with the packing rings 21, 22, and the anti-friction washers 29, 30, all rotate freely with the drill steel or bit 9 in the water head 1, and that the action of the pressure fluid on the packing rings 21, 22, makes the fluid-tight joint around the portion 8 of the shank 55 of the drill steel or bit 9 and between the washers 29, 30, and the raised surfaces 10, and so precludes the escape of the water along the outside of the portion 8 of the shank of the drill steel in either direction,

whilst allowing the various parts which are housed within the water head 1 to rotate freely with the drill steel or bit 9.

In the modified form of the invention shown in Fig. 4, the cylindrical casing is 70 constructed in three separate parts or sections, namely two end sections 31, 32, and an intermediate central section 33. Each of the end sections forms a housing for one of the hydraulic packing rings 21, 22, and 75 said end sections 31, 32, are constructed at their outer ends with inwardly directed flanges 34, 35, respectively, which serve as or take the place of the loose anti-friction washers 29, 30, of the construction illustrated in Figs. 1 to 3. If desired, anti-friction washers may be provided in addition to or in lieu of the flanges 34, 35.

The intermediate or centre section 33 is provided with the preferably radial holes 27 85 through which the water can pass from the water chamber 18 provided in the water head 1 to the transverse hole 14 in the portion 8 of the shank of the drill steel. This centre section 33 is grooved peripherally at 25, and lateral holes 28 are formed through both sides of said section 33 communicating with the radial holes 27 to allow of the passage 90 of the water from the water space 18 to the interior of the hydraulic packings 21, 22. 95

The screwed cap 6 of the water head 1 is shown provided at the front end with a renewable screwed bush 36 to provide the front 100 guide for the portion 8 of the shank of the drill steel or bit.

As is shown in dotted lines in connection with the hydraulic packing ring 21 in Fig. 3, helical or coiled spring 37 may be arranged inside either or both of the hydraulic packing rings 21, 22, so that said springs 37 105 will aid the water pressure to force the anti-friction washers 29, 30, the more tightly against the raised portions 10 at the ends of the water space 18. Obviously springs, such as 37, could be used in conjunction with 110 the modified form of the invention shown in Fig. 4.

By providing the raised surfaces 10 on the inner ends of the water head 1, and by reducing the outer ends of the end sections 31, 32, as indicated at 38, the pressure of the water in the water space 18 can act on portions of the washers 29, 30, or end sections 115 31, 32, and so counteract any excess of pressure that may be put on the washers 29, 30, 120 or flanges 34, 35, by the action of the water pressure on the hydraulic packing rings 21, 22.

What we claim as our invention and desire 125 to protect by Letters Patent is:—

1. Means for supplying water to rock-drills, including an outer stationary member which provides a water space and through which member the drill steel passes, two oppositely disposed hydraulic packing rings 130

arranged around the drill steel, and a casing which forms a housing for the packing rings, is loosely and completely housed in the stationary member, and is provided with passages through which the water can pass from the water space into the packing rings and to the drill steel, the packing rings and casing being rotatable with the drill steel in the stationary member, so that the outer transverse faces of the casing contact with the inner transverse faces of the housing to make the fluid-tight joint between the ends of the casing and the stationary member by the pressure of the fluid, as set forth.

2. Means for supplying water to rock-drills, including an outer stationary member which provides a water space and through which member the drill steel passes, two oppositely disposed hydraulic packing rings arranged around the drill steel, and a casing in which are housed the packing rings and which is loosely and completely housed in the stationary member and allows the water to pass from the water space into the packing rings and to the drill steel, the ends of the casing with the packing rings being able to move independently against transverse rigid jointing faces provided on the inner ends of the housing so that the fluid pressure automatically makes the joints between the pairs of transverse jointing faces between the casing and the stationary member, as set forth.

3. Means for supplying water to rock-drills, including a stationary water head through which the drill steel passes, two oppositely disposed hydraulic packing rings arranged around the drill steel, a casing which forms a housing for the packing rings, is loosely and completely housed in the water head and is provided with passages through which the water can pass from the water head to the packing rings and to the drill steel, and anti-friction washers arranged between the ends of the packing rings and the inner ends of the water head, the packing rings and casing being rotatable with the drill steel in the water head, so that the outer transverse faces of the washers contact with the inner transverse faces of the water head to make the fluid-tight joint between the washers and the water head by the pressure of the fluid, as set forth.

4. Means for supplying water to rock-drills, including a stationary water head through which the drill steel passes, two oppositely disposed hydraulic packing rings arranged around the drill steel, a casing which forms a housing for the packing rings, is loosely and completely housed in the water head and is constructed with an internal annular rib which forms a distance piece between the packing rings, and through which internal rib passages are formed to allow the water to pass from the water head into the packing rings and to the drill steel, and anti-friction washers arranged between the ends of the packing rings and the inner ends of the water head, the packing rings and casing being rotatable with the drill steel in the water head, so that the outer transverse faces of the washers contact with the inner transverse faces of the water head to make the fluid-tight joint between the washers and the water head by the pressure of the fluid, as set forth.

5. Means for supplying water to rock-drills, including a stationary water head through which the drill steel passes, two oppositely disposed hydraulic packing rings arranged around the drill steel, a casing which forms a housing for the packing rings, is loosely and completely housed in the water head and is constructed with an internal annular rib which forms a distance piece between the packing rings, and through which internal rib passages are formed to allow the water to pass from the water head into the packing rings and to the drill steel, and anti-friction washers arranged between the ends of the packing rings and the inner ends of the water head, the packing rings and casing being rotatable with the drill steel in the water head, the inner ends of the water head being constructed with raised surfaces with which the anti-friction washers rotate in contact, so that the outer transverse faces of the washers contact with the inner transverse faces of the water head to make the fluid-tight joint between the washers and the water head by the pressure of the fluid, as set forth.

In testimony whereof we have signed our names to this specification.

JAMES HENRY STUTHRIDGE.
THOMAS MOXHAY HACK.
